UNITED STATES PATENT OFFICE.

WILLIAM L. PAUL, OF BEAUFORT, NORTH CAROLINA.

COIN SORTER.

1,416,120.

Specification of Letters Patent. Patented May 16, 1922.

Application filed February 19, 1921. Serial No. 446,337.

To all whom it may concern:

Be it known that I, WILLIAM L. PAUL, a citizen of the United States, residing at Beaufort, in the county of Carteret and State of North Carolina, have invented 5 certain new and useful Improvements in Coin Sorters; and I do hereby declare the following to be a full, clear, and exact description of the invention, such as will enable others skilled in the art to which it appertains to make and use the same.

The present invention relates to a machine for sorting or separating coins or other articles, and aims to provide a novel 15 and improved construction and assemblage of parts to accomplish the sorting of the coins or articles in an efficient manner.

Another object is the provision of such a machine using rocking trays for separating 20 or sorting the coins or articles in a novel and efficacious manner.

A still further object is the provision in a contrivance of that character of novel means for discharging or delivering the coins or 25 articles and for counting them.

With the foregoing and other objects in view, which will be apparent as the description proceeds, the invention resides in the construction and arrangement of parts hereinafter described and claimed, it being 30 understood that changes can be made within the scope of what is claimed without departing from the spirit of the invention.

The invention is illustrated in the accompanying drawings, wherein:

Figure 1 is a front view of the machine.

Fig. 2 is a side elevation with the near side wall of the casing removed.

Fig. 3 is a similar view showing the parts 40 in position for discharging the coins from the trays.

Fig. 4 is a horizontal section on the line 4-4 of Fig. 2.

Fig. 5 is transverse section of one of the 45 trays.

Fig. 6 is a vertical section of one of the coin spouts showing the counting device.

Fig. 7 is a perspective view of the coin 50 lifting device of one tray, showing a slight modification also.

The working parts of the sorter are mounted within a suitable upright casing or frame 11, within the upper end of which is disposed a hopper 12 into which the coins 55 or articles to be separated are dumped so as to drop down into and pass through the

superposed sorting trays 13 within the casing below said hopper.

When a large number of coins are to be sorted, it is preferable to feed the coins 60 slowly into the hopper 12, and a feeder is therefore used above the hopper 12. Thus, a horizontal drive shaft 14 is journaled at the upper end of the casing, and has a hand crank 15 at one end for rotating said shaft 65 by hand, and a tapered drum 16 is mounted on said shaft, the larger end of said drum being open, and the drum having a lateral filling opening 17 adjacent to the smaller end. A cover 18 for the opening 17 is 70 hinged, as at 19, to the smaller end of the drum to normally fit over the drum and close said opening 17, and when the drum is stopped with the opening 17 at the top, the cover 18 can be swung open, as seen in 75 dotted lines in Fig. 3, thereby providing a hopper for conveniently dumping the coins into the drum. Then, when the cover 18 is closed and the shaft 14 rotated, the coins will work gradually to the larger end of the 80 drum and fall into the hopper 12 so as to be fed gradually into the trays 13. Such feeder, however, is unnecessary when small quantities of coins are to be sorted, when there is not a possibility of the coins choking 85 the machine or becoming clogged.

The superposed trays 13 are mounted for rocking or tilting movement on transverse rods 20 intermediate the ends of the trays, and said trays have parallel longitudinal 90 ribs 21 on the bottom thereof between which the coins can roll longitudinally forwardly and backwardly in the trays when same are rocked. The bottom of the trays have longitudinal slots 22 at the opposite ends thereof 95 between the ribs 21, through which the smaller coins can pass or drop, and these slots or openings of the trays are graduated. Thus, said slots decrease in length from the upper tray downward, whereby the coins 100 of the largest size cannot pass through the slots of the uppermost tray, such as 50 cent pieces, and the slots of the second tray are slightly shorter so as to prevent the coins of the next size, such as 25 cent pieces, 105 passing through, and so on down. In this way, the uppermost or first tray will arrest the largest coins and the successive trays will each arrest coins of gradually decreasing size. The first tray, when sorting 110 domestic denominations of coins, is for 50 cent pieces, the second tray for 25 cent

pieces, and the third tray for nickels and the fourth tray for pennies, while the dimes will pass on down and drop into a chute 13' below the lowermost tray.

5 In order to oscillate the trays, so that the coins will roll forwardly and backwardly thereof to enable the smaller coins to drop downwardly from one tray to the other until they reach their respective trays, a 10 pitman or link 23 connects a crank 24 of the drive shaft 14 with a lever 25 fulcrumed within the lower portion of the casing, and a link 26 connects the lever 25 with a second lever 27 that is in turn connected by a link 15 28 with the lowermost tray 13 near the rear end thereof. The several trays are connected together by a link 29, whereby they oscillate in unison. Consequently, when the shaft 14 is rotated, this will impart rocking or oscillating movement to the trays, and they swing forwardly and backwardly to oppositely inclined positions, as seen in Figs. 2 and 3.

Hinged accordion plates 30 are connected 25 to the ends of the trays 13 between the trays, and serve to close the ends of the spaces between the trays, whereby to prevent the coins from passing accidentally out from between the trays at the ends thereof. Such 30 plates being hingedly connected to one another and to the trays provide for flexibility so as to not interfere with the rocking motion of said trays.

In order to lift the coins out of the slots 35 22 of the trays, so that the coins will roll downwardly within the trays in either position, a coin lifter 31 is provided under each tray, and has the wings 32 and 33 extending forwardly and rearwardly, respectively, 40 longitudinally underneath the trays, and arranged at an obtuse angle with one another. The elbow or angle of said lifter 31 is hingedly mounted on the rod 20 of the corresponding tray, whereby said lifter can oscillate with the tray and also relatively to the tray to alternately move the wings 32 and 33 upwardly against the bottom of the tray. A supplementary coin lifting wing 34 is disposed over each forward wing 32 and 45 is hingedly connected to the corresponding rod 20, whereby said wing 34 can swing upwardly and downwardly with the wing 32 and upwardly away from the wing 32 against the bottom of the tray, as in Fig. 3, during 50 the discharging of the coins from the machine. The coin lifters 31 not only serve the office of raising the coins out of the slots 22 of the trays, but also serve as chutes or runways for the smaller coins to roll down 55 into the trays underneath.

The operating mechanism includes means for oscillating or rocking the coin lifters 31 in synchronism with the rocking motion of the trays, and, for this purpose, each lifter 60 wing 33 is connected by a link 35 with a

lever 36 fulcrumed to the back of casing, and a vertically slideable bar 37 is mounted in the casing and extends across the levers 26 for swinging them. The lower of the bar 37 is connected by a link 38 with the lever 25 for reciprocating said bar when the trays are rocked. Angular fingers 39 and 40 are pivoted to the bar 37 and their free terminals extend above and below the levers 36, respectively. The fingers 39 and 40 of each 70 pair are connected by a contractile spring 41 which tends to move or swing said fingers toward one another against stops 42 carried by the bar 37. When the rear ends of the trays are swung downwardly, as seen in Fig. 2, the bar 37 is also moved downwardly, and the upper fingers 39 will contact with the levers 36 and swing them downwardly, whereby to swing the wings 33 downwardly away from the trays and to 80 swing the wings 32 upwardly. The wings 34 are raised by the wings 32 and in contacting with the bottoms of the trays, will raise the coins out of the slots 22 of the trays at the forward ends thereof, so that the coins will roll rearwardly in the trays to drop in the slots at the rear ends of such trays, as seen in Fig. 2. When the trays are swung in the opposite direction, so that their forward ends move downwardly and their rear ends are moved upwardly, the wings 34 and 32 are moved downwardly with the forward ends of the trays, thereby raising the rear wings 33 and levers 36. However, the upward movement of the bar 37 is faster than 90 that of the levers 36, so that when the trays are moved beyond a horizontal position, the lower fingers 40 will come into contact with the levers 37 and swing said levers upwardly to move the wings 33 against the bottoms of the trays, as seen in Fig. 3, which will raise the coins out of the rear slots of the trays and they will roll forwardly in such trays. By this action, when the trays approach either inclined or tilted position, the coin 95 lifters are operated or oscillated to swing the corresponding wings upwardly against the upper end portions of the trays, and to move the other wings downwardly, whereby to lift the coins out of the slots of the trays near the upper ends, so that the coins will roll downwardly in the trays toward the opposite or lower ends. The springs 41 permit the 100 fingers 39 and 40 to yield when the movement of the levers 36 is stopped by the contact of either the forward or rear wings with the trays, and such springs will also provide for yielding action to make the reversing of the coin lifters quicker or more sharp in action, because the fingers can yield 105 and bring the springs 41 under tension before the levers 36 are swung to reverse the positions of the lifters 31. When one finger of either pair is swung away from its stop 42, the other finger is prevented from swing- 110 115 120 125 130

ing likewise by the corresponding stop, thereby stretching the spring 41.

In order that the sorted coins can be discharged from the trays 13, the forward ends 43 of such trays are hinged, as at 44, to the bottoms to swing forwardly and downwardly, and said ends have wings 44' extending at an angle therefrom to overlap the sides of the trays and to prevent the coins 10 rolling laterally off of said ends when they are swung downwardly, as seen in Fig. 3. The ends 43 are normally held closed by the springs 45 connected to said ends and corresponding side walls of the trays.

15 A device is employed for simultaneously moving the ends 43 of all of the trays downwardly to discharging position when the trays are in the position, as seen in Fig. 3, with their forward ends down, for the forward discharge of the coins. This device includes fingers 46 pivotally connected with a rod 47 which is connected at its upper end to a lever 50 and at its lower end with a coin-discharging lever 48 fulcrumed within the 20 casing and extending forwardly therefrom, and having a finger piece or button 49 at its forward end to be depressed. Springs 51 are provided between the fingers 46 and rod 47, whereby to hold said fingers in proper 25 position for operation, and to permit said fingers to swing yieldingly forwardly away from the rod, and the free ends of said fingers, which extend downwardly, are bifurcated, as at 52, to engage the outstanding lugs 53 carried by the ends 43 of the trays at one side of such trays where the rod 47 is located. When the forward ends of the trays are swung downwardly, the lugs 53 are brought to a position below the fingers 46, whereby when the lever 48 is depressed to 30 pull the rod 47 downwardly, the bifurcated ends 52 of said fingers move into engagement with said lugs 53, thereby pushing the ends 43 of the trays forwardly and downwardly 35 to discharging position, as seen in Fig. 3, said fingers swinging away from the rod 47. When the lever 48 is raised by its spring 54, it will raise the rod 47 and fingers 46, and the springs 51 will return said fingers to 40 normal position, while the springs 45 will swing the ends 43 back to closed position.

To prevent the coins dropping into the forward slots 22 of the trays during the discharge of the coins, the supplementary 45 wings 32 are raised, as seen in Fig. 3, to accomplish the discharge of the coins. Thus, levers 55 are fulcrumed within the casing and are swingable upwardly against outstanding lugs 56 carried by the wings 34 at 50 one side of the trays, and the levers 55 are connected by a link or rod 57 to swing simultaneously, while the lower end of said rod or lower lever is connected by a link 58 with the coin discharging lever 48. The levers 55 55 are normally in a position so as not to inter-

fer with the wings 34, but when the trays are in discharging position, as seen in Fig. 3, and the lever 47 is depressed, the links 58 and 57 are pulled downwardly thereby swinging the levers 55 into engagement with the lugs 56 and raising the wings 34 up against the bottoms of the trays. The wings 34 are thus swung upwardly away from the wings 32 to raise the coins out of the forward slots 22 of the trays and to enable the 75 coins to roll down the trays and out across the forward open end thereof, as depicted in Fig. 3.

Receptacles are provided for catching and holding the various denominations or sizes 80 of coins, and include chutes 59 carried by the front wall of the casing and registering with openings 60 provided in said wall, and said chutes have landings 61 so arranged that the ends 43 of the trays move against 85 or adjacent to said landings when swung to discharging position, as seen in Fig. 3. A similar chute 59 is also provided at the forward end of the runway or chute 13' below the lowermost tray for receiving the smallest 90 size of coins or dimes. These chutes 59 are extended laterally in opposite directions and in staggered relation and terminate in depending coin spouts 62 into which the coins roll and pile up in stacks. 95

The spouts 62 are provided with means for supporting the coins therein and for discharging the coins in predetermined numbers, whereby the coins can be readily counted. Thus, a lower dog or detent 63 is 100 slideable through one side of each spout and is linked to an arm 64 of a lever 65 which is fulcrumed to a bracket 67 extending from said spout. An upper dog or detent is also slideable in said side of the spout and is 105 linked to an arm 68 also fulcrumed to the bracket 67, and a spring 70 is located between the arm 69 and lever 64. The dog 68 is normally retracted, while the lower dog 63 is normally projected into the spout, to 110 support the stack of coins, and said dogs are spaced apart sufficiently to have a predetermined number of coins between them, such as ten, fifteen, twenty or more, to facilitate counting. Each spout has a window or 115 opening 71 above the dog 68, in order that the operator can observe when the spout is filled sufficiently for the discharge of the predetermined number of coins. Then, by pushing the lever 65, this will withdraw the 120 dog 63 from below the coins and at the same time, the dog 68 is pushed into the spout by the compression of the spring 70, thereby supporting the coins above said dog 68, and permitting the coins below said dog 68 to 125 drop out of the spout into the hand placed below the spout or into some suitable receptacle. A predetermined number of coins is thus discharged, for convenient counting. The inner end of the dog 68 is sharpened 130

whereby to pass readily between the coins, but, should the coin be worn, then it is possible that the coin which should be above the dog 68 is in substantially the same plane. 5 In this case, when the lever 65 is swung, the dog 68, instead of being projected into the spout, will contact with the corresponding coin and the compression of the spring 70 will cause the dog 68 to press tightly against 10 the edge of such coin and hold it tight in the spout, to support the other coins above the same, and enable the coins below to drop from the spout. When the lever 65 is returned, the dog 68 is also retracted, and the 15 dog 63 again projected into the spout, whereby the remaining coins will drop down past the dog 68 and come to rest on the dog 63. The operation of the machine is as follows: The coins to be sorted are dropped 20 gradually into the hopper 12, either by hand or by the feeder 16, and will drop down into the upper tray 13. During the delivering of the coins into the machine, the crank 15 is rotated, whereby to rock the 25 trays back and forth and to also reciprocate the bar 37. When the rear ends of the trays are swung upwardly, the bar 37 is also moved upwardly, and the wings 34 and 32 are moved downwardly with the forward ends of the trays, thereby raising the 30 wings 33 and levers 36. However, the bar 37 moves faster than the levers 36, whereby the lower fingers 40 come into contact with said levers, and just before the rear ends 35 of the trays reach their uppermost position, the lower fingers 40 will swing the levers 36 to swing the wings 33 up against the bottoms of the trays, as seen in Fig. 2. This will swing the wings 32 downward away 40 from the trays and the wings 34 will also drop downwardly with said wings 32. Consequently, the coins which previously dropped into the rear slots 22 of the trays, 45 will be lifted out of said slots and will roll downwardly in the grooves or channels of the trays formed by the ribs 21, and will drop into the forward slots of the trays, the smaller coins passing down through and rolling down the wings 34 into the 50 trays underneath. Then, when the forward ends of the trays are raised, and the rear ends lowered, the bar 37 is also lowered, and the wings 33 move downwardly with the trays and also swing the levers 36 downwardly. Before the rear ends of the trays 55 reach their lowermost position, the bar 37 will have moved sufficiently faster than the levers 36 to bring the fingers 39 into contact with said levers 36, whereby to swing said 60 levers downwardly and move the wings 33 away from the trays, as seen in Fig. 2, thereby raising the wings 32 and 34 upwardly against the trays. Consequently, the coins in the forward slots 32 are raised 65 out of said slots and they will roll rear-

wardly in the trays and drop into or through the rear slots. The coins which drop through the slots will roll down the rear wings 31 into the trays underneath. In this way, as the trays are rocked back and forth the coins are rolled forwardly and rearwardly in the trays, whereby the smaller coins will pass on down until they reach their respective trays in which they remain, while the smallest size of coins will drop into the runway 13' and roll immediately down into the lowermost coin receptacle. The oscillation of the trays is continued as long as coins are fed into the machine, and until the sorting is completed, 75 which will require a few oscillations after the last coin is fed into the machine. Then, to discharge the coins from the trays, they are swung to the position as seen in Fig. 3, with their forward ends down. The lever 80 48 is then depressed, which will swing the levers 55 so as to raise the wings 34 against the trays, and the rod 47 is simultaneously depressed so that the fingers 46 engaged the lugs 53 and swing the ends 43 of the trays 85 downwardly against or adjacent to the landings 61. The coins will therefore roll from the trays into the chutes 52 and drop into the spouts 62, from which the coins can be taken and counted conveniently. When 90 the spouts are filled, and the levers 65 operated as above described, predetermined numbers of coins are discharged from the spouts, but when the spouts are only partly filled it is necessary to individually count 95 the coins. 100

As shown in Fig. 7, the edges of the wings 32 and 33 of each coin lifter 31 can have upturned flanges 32' to overlap the side walls of the tray and prevent the coins from rolling sideways off of said wings from between the trays. 105

By keeping a record of the number of times each lever 65 is operated with the spout full of coins, the total number of 110 coins is readily recorded, and, if desired, any suitable register can be used for registering the number of times that each lever 65 is operated, which is hardly thought necessary to illustrate in detail. 115

Having thus described the invention, what is claimed as new is:—

1. A sorter comprising a rocking tray having sorting openings at opposite ends, and means operable for lifting articles out 120 of said openings at each end of the tray when it is in raised position.

2. A sorter comprising a movable tray having longitudinal channels for the rolling movement of coins and similar articles therein longitudinal of the tray, the bottom of the tray having longitudinal slots in which the coins or articles can drop, and such slots being of a length to permit the smaller coins or articles to pass through, and means 125 130

- cooperable with the tray for lifting the larger coins or articles out of said slots to roll in said channels.
3. A sorter comprising a rocking tray having longitudinal channels for the articles to roll in and having sorting openings at opposite ends in said channels for the article to drop down in or through, and means operable for lifting the articles out 10 of said openings at each end of the tray when such end is in raised position.
4. A sorter comprising a rocking tray having sorting openings at its opposite ends, and lifting means having wings alternately 15 movable toward the tray for lifting the articles out of said openings at the opposite ends when such ends are in raised position.
5. A sorter comprising a rocking tray having sorting openings at its opposite ends, 20 lifting means having wings alternately movable toward the openings at the opposite ends of the tray, and an actuating mechanism for rocking the tray and operably connected with said lifting means to move the 25 wings toward said openings, respectively, when the ends of the tray are in raised position.
6. A sorter comprising a tray mounted between its ends for rocking movement and 30 having sorting openings in its bottom at the opposite ends, and lifting means below the tray operable for lifting the articles up out of said openings at either end when such end is in raised position.
- 35 7. A sorter comprising a tray mounted between its ends for rocking movement and having sorting openings at its opposite ends, and lifting means below the tray including a pair of wings alternately movable up- 40 wardly toward the bottom of the tray under the opposite openings for raising the articles out of the openings when the corresponding ends of the tray are in raised position.
8. A sorter comprising a tray mounted 45 between its ends for rocking movement and having sorting openings in its bottom at the opposite ends, lifting means below the tray including a pair of wings underneath the opposite openings, and actuating means for 50 rocking the tray and operably connected with said wings for alternately raising the wings and lifting the articles out of the openings when the corresponding ends of the tray are in raised position.
- 55 9. A sorter comprising a rocking tray having sorting openings in its bottom at the opposite ends, a lifter having opposite wings at an angle with one another and mounted 60 for oscillation to alternately raise said wings under the opposite openings, and actuating means for rocking the tray and oscillating said lifter to lift the articles out of said openings when the corresponding ends of the tray are in raised position.
10. A sorter comprising a rocking tray 65 having sorting openings, and lifting means operable for lifting articles out of said openings when the tray is inclined so that the articles roll down the tray.
11. A sorter comprising a tray movable to 70 opposite inclined positions for the rolling action of articles therein back and forth, and having sorting openings in the bottom thereof, and means cooperable with the tray for lifting the articles out of said openings in 75 the opposite inclined positions of the tray, so that the articles will roll within the tray.
12. A sorter comprising a rocking tray having sorting openings and an end which is adapted to open for the discharge of the 80 articles from said end, and means operable for lifting the articles out of said openings for the rolling movement of the articles in the tray when same is being rocked and also for the discharge of the articles when 85 said end is in lowered position and opened.
13. A sorter comprising a rocking tray having sorting openings for objects to drop into, and having an end movable to open 90 position for the discharge of the articles from said end of the tray, lifting means operable for lifting the articles out of said openings when the tray is inclined so that the articles roll within the tray when it is rocked to different positions, and supplementary means for lifting the articles out of the openings when said end is opened. 95
14. A sorter comprising a rocking tray having sorting openings at its opposite ends and having one end movable to open position for the discharge of the articles from 100 said tray at said end, a lifter having wings at an angle with one another to alternately move upwardly adjacent to the bottom of the tray below the respective openings at 105 the opposite ends, means for rocking the tray and oscillating said lifter to lift the articles out of the openings at the raised ends of the tray, respectively, a supplementary wing above one of the aforesaid 110 wings at said end of the tray, and means for opening said end of the tray when it is in lowered position and for raising said supplementary wing.
15. A sorter having superposed rocking 115 trays with sorting openings in the bottoms thereof for sorting articles, each tray having one end normally preventing the passage of the articles and arranged to be moved open, means for opening said ends of the trays, and receptacles for receiving the articles from said ends of the trays. 120
16. A sorter comprising superposed rocking trays having sorting openings in the bottoms thereof, each tray having a hinged 125 end adapted to swing open downwardly, means for swinging said ends when they are in lowered position with the opposite ends

of the trays raised, and receptacles with which said opened ends of the trays cooperate to receive the articles from the trays.

17. A sorter comprising superposed trays having sorting openings in the bottom thereof at the opposite ends, transverse rods between the ends of the trays on which they are mounted for rocking movement, each tray having one end arranged to open for the discharge of the articles from the tray, lifters embodying opposite wings at an angle with one another and mounted for oscillatory movement on said rods under the respective trays to swing upwardly under the opposite openings alternately, supplementary wings hingedly mounted on said rods above those aforesaid wings adjacent to said ends of the trays, actuating mechanism for rocking the trays operatively connected with said lifters for oscillating said lifters to alternately raise the opposite wings thereof for lifting the articles out of the openings of the trays when the corresponding ends are raised, means operable when said ends are lowered for opening them and for raising the supplementary wings to lift the articles out of the corresponding openings, and receptacles for receiving the articles from said opened ends.
18. A sorter comprising a tray movable for rolling articles therein back and forth and having sorting openings in the bottom thereof for the passage of the smaller articles, and means for lifting the larger articles out of said openings for rolling movement from one portion of the tray to another.

19. A sorter comprising a tray movable for rolling articles therein back and forth

and having sorting openings in the bottom thereof for the passage of smaller articles, said tray having a portion for normally preventing the articles from rolling out of the tray and adapted to be opened to permit the articles to roll out of the tray, and means for lifting the larger articles out of said openings to roll from one portion of the tray to another.

20. A sorter comprising a tray channeled for the rolling motion therein of coins or other articles and having openings in the bottom thereof for the passage of the smaller articles, and means for lifting the larger articles out of said openings to roll in the channeled portion of the tray from one point to another.

21. A sorter comprising a tray channeled for the rolling motion of coins or other articles therein and movable for such rolling motion of the articles back and forth, the tray having sorting openings in the bottom thereof for the passage of the smaller articles, the tray having a portion for normally preventing the articles from rolling out of the tray and adapted to be opened for the discharge of the articles from the tray, and means operable for lifting the articles out of said openings for rolling movement in the tray from one point to another along the channeled portion.

In testimony whereof I have signed my name to this specification in the presence of two subscribing witnesses.
